Attorney.

UNITED STATES PATENT OFFICE.

THEOPHILUS MATTHEWS, OF FLEUR-DE-LIS, WALES.

SPRING-FRAME FOR MOTOR-CYCLES.

1,261,838.

Specification of Letters Patent.

Patented Apr. 9, 1918.

Application filed July 24, 1917. Serial No. 182,459.

To all whom it may concern:

Be it known that I, THEOPHILUS MATTHEWS, a subject of the King of Great Britain and Ireland, and a resident of Fleur-de-Lis, county of Monmouth, Wales, have invented certain new and useful Improvements in and Relating to Spring-Frames for Motor-Cycles, (for which I have obtained a patent in Great Britain, No. 101,615, dated 10 July 28, 1916,) of which the following is a specification.

This invention relates to spring frames for the rear wheels of motor cycles for absorbing road shocks caused by the unevenness of 15 the road or by the wheel striking an obstacle.

The present invention consists in certain novel features of construction and arrangement of parts as herein set forth and pointed 20 out in the appended claims.

The invention is illustrated by the accompanying sheets of drawings in which:—

Figure 1 is a side view of the complete device partly in section.

Fig. 2 is an end view of the main bearing plate, top bearing plate and the springing.

Fig. 3 is a sectional plan view of a spring-controlled slideable and pivotal connection hereinafter referred to.

Fig. 4 is a side view of a modified form of arrangement shown in Fig. 1.

Like letters of reference indicate corresponding parts in the several figures.

In carrying out the invention, and referring first to Figs. 1, 2 and 3, the improved frame consists of:—

(1) a top member *a* pivotally mounted at *b* to the top of the seat tube *e*, said top member *a*, which also forms the back carrier, being formed of tubing bent to appropriate shape;

(2) L-shaped top bearing plates *d*, one at each side of the wheel *e* and stays *f*, *f'* connecting said L-shaped top bearing plates 45 with the rear end of the top member *a* and the pivot *b* to which said top member *a* is pivoted;

(3) L-shaped main bearing plates *g*, one at each side of the wheel *e* and in the alignment with the top bearing plates, said bearing plates *g* receiving the ends of the wheel spindle *h*;

(4) Vertically and centrally disposed tubes *i* fixedly secured to the top frame *a* and the top plates *d*;

(5) Vertically disposed tubes *j* fixedly se-

cured to the bottom plates *g* and slidably mounted in the vertical tubes *i*, which tubes *i* are closed at the bottom by an oil-retaining stuffing box or gland *i''*;

60

(6) Spiral springs *k* interposed between and bearing against said top and bottom plates, and guide rods *m*, one at each side of the vertical tubes, said guide rods *m* which extend through said springs being fixedly secured to the top plates *d* but slideable through the bottom plates, *g*;

65

(7) Chain stays *n* pivotally connected at *o* to the bottom plates *g*;

70

(8) The improved arrangement of spring-controlled slideable and pivotal connection between the chain stays and the lower end of the seat tube to take the backward shock when the wheel *e* strikes against any obstruction.

75

In action, unevenness of the road causing the wheel *e* to ride upward compresses the springs *k* between the top and bottom plates *d* and *g*, the tube *j* sliding in the tube *i* and the guide rods *m* sliding in the bottom plates *g*, and thus the shock is absorbed.

80

In the event of the wheel *e* striking an obstacle, the backward shock to said wheel is absorbed or taken up by the following device which consists of, as shown most clearly in Fig. 3, a crown piece *n'* connecting the chain stays *n* and bored for the passage therethrough of a stud *n²* fixedly mounted in an eye piece *n³* which is pivotally mounted on the pin *n⁴* mounted in the lugs *n⁵* at the lower end of the seat tube, and between such crown piece *n'* and a screw nut and washer *n⁶* is interposed a strong spring *n⁷*, which spring *n⁷* is compressed by the crown piece *n'* (and with it the chain stays *n*) sliding backward on the stud *n²*. The obstruction being passed, the spring *n⁷* carries the crown piece forward again to its original position.

85

As some motor cycles are arranged to be propelled by foot power, there is provided a tubular stay or the like *n⁸* for the reception of the spindle of a sprocket wheel *n⁹* (indicated by dot-and-dash lines in Fig. 1) and the usual cranks and pedals as at present obtains.

90

Referring now to Fig. 4 it will be seen that the arrangement of springing is reversed, that is to say, the guide rods *m* instead of being fixed in the upper L-shaped bearing plates *d* and sliding in the lower L-shaped bearing plates *g*, are now fixed in

95

100

105

110

said lower bearing plates *g* and are slidable in the upper bearing plates *d*, and said rods *m* are extended above said bearing plates *d* and provided with heads *r* for the reception 5 of springs *s* which serve to take up the rebound.

Further the chain stays *n* instead of being made extensible and spring-controlled and pivotal are now inextensible and are pivoted 10 by their ends at *o* and *n*⁴ to the bottom bearing plates *g* and the lug *n*⁵ at the lower end of the seat tube *c*.

Further the top member *a* of the spring frame and the front stays *f*' are now rigidly attached at *b* to the seat tube *c* instead of pivotally as in the previous arrangement, and the rear stays *f* are now preferably bent or crank so as to receive a tool box *t* carried between said stays and the central 20 tube *i*.

Having now described my invention, what I claim as new and desire to secure by Letters Patent of the United States is:—

1. In spring frames for the rear wheels 25 of motor cycles, the combination of a top frame which forms the back carrier attached to the top of the seat tube, L-shaped top bearing plates and stays connecting said top bearing plates to the top frame and the 30 seat tube, L-shaped bottom bearing plates which receive the back wheel spindle, centrally and vertically disposed tubes carried by said bottom plates and slidably mounted in centrally disposed tubes carried by and 35 fixed to the top plates, springs interposed between said top and bottom plates, and guide rods fixedly carried by one set of plates but slidable in the other set of plates, said guide rods extending through said 40 springs, and chain stays pivotally connected to the bottom L-shaped bearing plates and to lugs at the lower end of the seat tube.

2. In spring frames for the rear wheels 45 of motor cycles, the combination of a top frame pivotally secured to the seat tube, said top frame forming the back carrier, L-shaped top bearing plates and stays connecting said top bearing plates to the top frame and to the pivot of the frame, L-shaped

bottom bearing plates which receive the 50 back wheel spindle, centrally and vertically disposed tubes carried by said bottom plates and slidably mounted in centrally disposed tubes carried by and fixed to the top plates, springs interposed between said top and 55 bottom plates, and guide rods fixedly carried by the top plates but slidably in the bottom plates, said guide rods extending through said springs, chain stays, a crown piece connecting said stay and slidably 60 mounted on a stud fixedly secured to an eye piece pivotally mounted in lugs at the lower end of the seat tube, a screw nut and washer on said stud, and a spring interposed between said washer and said crown piece. 65

3. A spring frame for the rear wheels of 70 motor cycles including in combination with the seat tube of the cycle frame and the axle of the rear wheel, supporting elements carried by the rear axle, a skeleton frame 75 adapted to be positioned above the wheel and having one end thereof connected to the seat tube, shock absorbing means interposed between the lower portion of the said frame and supporting elements, and means having one end connected to the supporting elements 80 and the other end resiliently connected to the seat tube. 75

4. A spring frame for the rear wheels of 85 motor cycles including in combination with the seat tube of the cycle frame and rear axle, a top frame connected to the seat tube, supporting plates carried by the rear axle, means pivotally connecting the said supporting plates with the seat tube, stay members carried by and depending from the top frame, other plates connecting with the lower ends of certain of the stay members, guide elements interposed between said latter plates and the supporting plates, and 90 springs fitted to certain of said guide elements and abutting against said plates. 90

In testimony whereof I have affixed my signature in presence of two witnesses.

THEOPHILUS MATTHEWS.

Witnesses:

EDGAR DAVIES,
JOHN HUGHES.
